ALKAMINE DERIVATIVES OF ETHERS OF
p-HYDROXYMETHYL BENZOIC ACID

Victor S. Salvin, Cumberland, Md., and Arthur J. Hill, New Haven, Conn., assignors to American Cyanamid Company, New York, N. Y., a corporation of Maine

No Drawing. Application April 16, 1942,
Serial No. 439,234

16 Claims. (Cl. 260—471)

This invention relates to the alkyl esters of p-alkamineoxy-methyl benzoic acid and to methods of preparing the same.

According to the present invention we have found that a new series of compounds can be prepared, many of which have high potency as local anesthetics for surface and intracutaneous use, some of which compounds have activities comparable to cocaine accompanied with lower toxicity. The compounds of the present invention are alkyl esters of p-alkamineoxymethyl benzoic acids and may be represented by the following formula:

in which Alk is an alkyl radical and R is an alkamine, the ether oxygen being joined to a carbon atom of the alkamine group. The alkamine group may be a secondary or tertiary amine but the most important products covered by the present invention are those in which the alkamine is tertiary which may be represented by the following formula:

in which Alk is an alkyl radical, Alk₂ is an alkylene radical, and Alk₃ and Alk₄ are the same or different alkyl groups. The alkylene radical, Alk₂, may be straight chain or branch chain.

While the products of the present invention are not limited to any particular method of preparation, I prefer to use a process in which an ester of p-halogen methylbenzoic acid is reacted with an alcoholate of the desired aminoalcohol. The reaction proceeds smoothly with good yield, and in a more specific aspect, the preferred process is included in the present invention.

The cheapest intermediates to use are the p-chloromethylbenzoic acid esters, but the p-bromomethyl compound may also be used, the reaction proceeding with excellent yield and great ease, but for most compounds the additional cost of the brom intermediate over the chlor intermediate is not warranted.

The esters of the present invention are secondary or tertiary amines and form the usual salts such as hydrochlorides, sulfates, borates and the like. The salts of the bases are therefore included in the invention and in fact the crude product obtained by extraction with dilute hydrochloric acid is the hydrochloride rather than the free base. Quaternary nitrogen salts may also be prepared such as for example the methiodides, ethobromides and the like.

The invention will be described in greater detail in conjunction with the following specific examples which are typical illustrations. The parts are by weight.

EXAMPLE 1

Ethyl-p-β-diethylaminoethoxymethyl benzoate

23 parts of sodium are dissolved in 250 parts of β-diethylaminoethanol which represents an excess of the alcohol. After formation of the alcoholate excess amino alcohol is removed by distillation under reduced pressure and 1500 parts of dry benzene added to the residual salt. 98 parts of ethyl p-chloromethyl benzoate dissolved in 600 parts of benzene are then slowly added with stirring, the temperature of the reaction mixture being maintained sufficiently high throughout the addition so that gentle refluxing of the benzene takes place. After all of the ester is added, refluxing is maintained for a considerable period until the reaction is complete.

The benzene reaction mixture is then extracted with cold dilute hydrochloric acid and the extract neutralized with a slight excess of sodium hydroxide in order to precipitate the basic oils which are then extracted with ether, the extract washed with water, dried and the ether removed by distillation. A residual liquid remains which contains the desired product together with a certain amount of unreacted amino alcohol. Distillation is effected at reduced pressure (4 mm.) the amino alcohol coming off first and the alkamine ether ester coming off in a fraction boiling between 175 and 180° C. This fraction is then redistilled and a straw colored oil is obtained in good yield and boiling in the range of 176–178° C. at 4 mm. The product shows anesthetic activity comparable to cocaine with much lower toxicity.

EXAMPLE 2

*Ethyl-p- γ -diethylaminopropoxymethyl benzoate*23 parts of sodium are dissolved in 320 parts of γ -diethylaminopropanol and the excess amino alcohol is removed by distillation under reduced pressure. 500 parts of benzene were then added and 198 parts of ethyl-p-chloromethylbenzoate dissolved in 500 parts of benzene gradually introduced into the solution with continuous agitation. Reaction starts immediately, the reaction mixture heats up and a solid (sodium chloride) precipitates. After the addition of all of the ester the reaction mixture is refluxed and stirred for a considerable period until no more solid precipitates.

The reaction mixture is then cooled and extracted with cold dilute hydrochloric acid. This acid extract containing the hydrochloride of the alkaline ether ester is then made alkaline with solid sodium carbonate and the liberated alkaline ether ester extracted with ether. After drying the ether extract, the ether is removed and the residual liquid purified by fractional distillation under reduced pressure (3 mm.). At first some unreacted amino alcohol distills off and the ether ester fraction then comes over at about 175 to 180° C. yielding a product which on redistillation is a light colored liquid boiling at 177 to 179° C. (3 mm.). The yield is slightly under 50%. A considerable portion of the remainder of the reactants can be recovered in the form of a high boiling fraction boiling about 200° C. (3 mm.) and constitutes a symmetrical γ -diethylaminopropylether ester, the ethyl grouping having been replaced with amino alcohol by alcoholysis. The product is a useful pharmaceutical, showing anesthetic activity slightly less than that of Example 1 with the same low toxicity.

EXAMPLE 3

*Ethyl-p- γ -dibutylaminopropoxymethyl benzoate*The process of Examples 1 and 2 is followed except that 460 parts of γ -dibutylaminopropanol is substituted for 320 parts of γ -diethylaminopropanol. After extracting with hydrochloric acid, neutralizing and extracting with ether, a liquid is obtained which is fractionally distilled. At first some unreacted amino alcohol comes over and the major portion of the liquid then distills from 195–199° C. (3 mm.). On redistillation the boiling range can be reduced to 196–198° C. at the same pressure. A considerable by-product is obtained as a high boiling fraction coming over at above 232° C. As in the case of Example 2 this fraction represents a by-product in which the amino alcohol has replaced ethyl alcohol in the ester group by alcoholysis. This by-product is also a useful pharmaceutical and shows slightly lower anesthetic activity than Example 1, but still lower toxicity.

EXAMPLE 4

*Butyl-p- β -diethylaminoethoxymethyl benzoate*10 12 parts of sodium are dissolved in an excess (200 parts) of β -diethylaminoethanol. The excess amino alcohol is then removed under reduced pressure and 500 parts benzene added. 120 parts of butyl-p-chloromethyl benzoate (prepared by esterifying p-chloromethylbenzoic acid with butanol) are dissolved in 500 parts of benzene and the solution added gradually to the alcoholate solution. The mixture heats up and after all of the ester is added refluxing is continued until the reaction is complete which takes several days.

15 The reaction mixture is cooled, extracted with dilute hydrochloric acid and the acid extract neutralized with sodium carbonate liberating the unreacted amino alcohol and the amino ester. The 20 solution is then extracted with ether and the ether extract dried, ether removed and the residual liquid subjected to fractional distillation at low pressure (2 mm.). Unreacted amino alcohol comes over first and the desired ester is obtained in a fraction boiling between 170 and 175° C. which on redistillation has a boiling range of 25 173–174° C. It is a faintly yellow oil, the yield being approximately 50%. The product is a more active local anesthetic than cocaine with greatly 30 reduced toxicity. A high boiling fraction coming over above 190° C. is also obtained which is the corresponding alkamine ester produced by alcoholysis of the ether ester with excess amino alcohol. This product is also a useful pharmaceutical.

EXAMPLE 5

*Butyl-p- β -diethylaminopropoxymethyl benzoate*The procedure of Example 4 is followed using 55 corresponding amounts of β -diethylaminopropanol in place of the β -diethylaminoethanol. The product obtained is a light colored oil having 60 properties closely resembling that of the corresponding β -diethylaminoethoxymethyl compound. Alcoholysis also takes place producing a considerable quantity of a high boiling fraction in which the diethylaminopropanol has replaced the butyl radical by alcoholysis.

The examples describe alkamine ether esters of 65 some of the more common amino alcohols. The reaction by which the ether esters are made, however, is quite general and applicable to any amino alcohol which is capable of forming alcoholates. It should also be noted that the substituents on the nitrogen do not have to separate alkyl chains but may form part of a ring such as a piperidine 70 or morpholine ring. Examples of other alcohols which can be used to produce the corresponding ether esters are the dibutylaminobutanol, β , β -phenylethylaminoethanol, β -dipropylaminoethanol, β -morpholinoethanol, β -piperidinoethanol, 75 β -dicyclohexylaminoethanol, β -methylcyclohex-

ylaminoethanol, β -phenylaminoethanol, β,β -dimethyl- γ -piperidinopropanol and the like.

We claim:

1. An ester of p -di-alkylaminoalkoxymethyl benzoic acid.
2. An ester of a p -dialkylaminoalkoxymethyl benzoic acid having the following formula:

in which R is an alkylene radical and Alk₁, Alk₂ and Alk₃ are alkyl groups.

3. An ester of a p -(omega-dialkylaminoalkoxy-methyl) benzoic acid having the following formula:

in which Alk₁, Alk₂ and Alk₃ are alkyl groups.

4. A salt of an ester according to claim 2.
5. A salt of an ester according to claim 3.
6. An ester of p - β -diethylaminoethoxymethyl benzoic acid.
7. A salt of an ester of p - β -diethylaminoethoxymethyl benzoic acid.

8. A butyl ester of p - β -diethylaminoethoxymethyl benzoic acid.
9. A salt of a butyl ester of a p - β -diethylaminoethoxymethyl benzoic acid.
10. The butyl ester of p - γ -dibutylaminopropoxy benzoic acid.
11. A salt of the butyl ester of p - γ -dibutylaminopropoxymethyl benzoic acid.
12. A process of preparing an alkyl ester of an alkylaminoalkoxymethyl benzoic acid which comprises reacting a p -halogen-methyl alkyl benzoate with an alcoholate of an alkylamino alcohol.
13. A method of preparing an alkyl ester of a dialkylaminoalkoxymethyl benzoic acid which comprises reacting an alkyl ester of p -halogen-methyl benzoic acid with an alcoholate of a dialkylamino alcohol.
14. A method of preparing ethyl p - β -diethylaminoethoxymethyl benzoate which comprises reacting ethyl p -chlormethyl benzoate with an alkali metal alcoholate of β -diethylaminoethanol.
15. A method of preparing p - β -diethylaminoethoxymethyl benzoate which comprises reacting butyl p -chlormethyl benzoate with an alcoholate of β -diethylaminoethanol.
16. A method of producing butyl p - γ -dibutylaminopropoxymethyl benzoate which comprises reacting butyl p -chlormethyl benzoate with an alcoholate of γ -dibutylaminopropanol.

VICTOR S. SALVIN.
ARTHUR J. HILL.

Certificate of Correction

Patent No. 2,350,826.

June 6, 1944.

VICTOR S. SALVIN ET AL.

It is hereby certified that error appears in the printed specification of the above numbered patent requiring correction as follows: Page 3, second column, lines 5—6, claim 10, for "p- γ -dibutylaminopropoxy" read *p- γ -dibutylaminopropoxymethyl*; and that the said Letters Patent should be read with this correction therein that the same may conform to the record of the case in the Patent Office.

Signed and sealed this 7th day of November, A. D. 1944.

[SEAL]

LESLIE FRAZER,
Acting Commissioner of Patents.
